UNITED STATES PATENT OFFICE.

FREDERICK WEHINGER, OF WATERBURY, CONNECTICUT, ASSIGNOR TO WATERBURY CLOCK COMPANY, OF WATERBURY, CONNECTICUT, A CORPORATION.

CENTER-FRICTION FOR WATCHES AND CLOCKS.

958,987.

Specification of Letters Patent. Patented May 24, 1910.

Application filed February 17, 1910. Serial No. 544,440.

To all whom it may concern:

Be it known that I, FREDERICK WEHINGER, a citizen of the United States, residing at Waterbury, in the county of New Haven and State of Connecticut, have invented a new and useful Improvement in Center-Friction for Watches and Clocks; and I do hereby declare the following, when taken in connection with the accompanying drawings and 10 the characters of reference marked thereon, to be a full, clear, and exact description of the same, and which said drawings constitute part of this specification, and represent, in—

15 Figure 1 a view partly in side elevation and partly in vertical section of a center-friction constructed in accordance with my invention. Fig. 2 a detached view in side elevation of the friction-collar. Fig. 3 a 20 detached edge view of the friction-washer. Fig. 4 a detached plan view of the friction-washer. Fig. 5 a detached view in side elevation of the center-pinion. Fig. 6 a broken 25 view partly in side elevation and partly in vertical section of one of the modified forms which my improved center-friction may assume. Fig. 7 a detached view in side elevation of the friction-collar. Fig. 8 a detached 30 edge view of the friction-washer. Fig. 9 a detached view in side elevation of the center-pinion.

My invention relates to an improved center-friction for watches and clocks, or in other words, to that feature of watches and 35 clocks employed to permit the center-arbor or shaft carrying the hands to be turned one way or the other, as required for setting them, without disturbing the time-train of the movement, the object of my present invention being to produce a center-friction constructed with particular reference to securing a marked economy of space as well as a smoother and more uniform frictional action than the corresponding devices of the 40 prior art.

With these ends in view my invention consists in the construction and combination of parts to be hereinafter described and pointed out in the claims.

50 In carrying out my invention as herein shown, I employ a flat washer 2 which is cupped and therefore placed under tension by being compressed between a friction-collar 3 having a convexed face 4 and non- 55 rotatably mounted upon the center-arbor 5,

and the concaved adjacent face 6 of the center-pinion 7 loosely mounted upon the said arbor 5, and carrying the center-wheel 8 which forms a part of the time-train of the movement.

60 The tension of the washer 2 crowds the pinion 7 and wheel 8 forward so as to create between the forward end of the said pinion and a shoulder 9 on the arbor 5, the friction required to cause the arbor 5 to be rotated by the wheel 8 under ordinary conditions. When, however, it is desired to set the hands, not shown, but understood to be applied in the usual manner to the forward 65 end of the arbor, the same will turn independently of the pinion 7 and wheel 8 by the application to it of a power superior to the friction produced as described. My improved construction above set forth is more economical of lateral space than the ordinary 70 cupped washer and produces a smoother and more uniform friction inasmuch as it is very difficult to temper the metal used in cupped washers with sufficient accuracy and uniformity to make them give uniform results. 75

80 In the modified form of my invention shown by Figs. 6 to 9 inclusive, the construction shown by the preceding figures is reversed, but the operation is the same. In this construction the friction-collar 10, non-rotatably mounted upon the center-arbor 11, has its forward face concaved as at 12 for coaction with a flat washer 13 sprung into such concavity by being forced against a convex surface 14 formed at the rear end of the center-pinion 15 loosely mounted upon the arbor 11 and carrying a center-wheel 16 which is in mesh with the time-train of the movement. The tension thus produced creates sufficient friction between the forward end of the pinion 15 and a shoulder 17 upon the arbor 11, to cause the same to be rotated under normal circumstances with the wheel 16, but this tension is easily overcome for setting the hands by the application of enough power to the arbor 11 to overcome the tension of the washer 13.

90 I claim:—

95 In a watch, the combination with the center-arbor thereof, of a friction shoulder located upon the said arbor, a center-pinion 105 loosely mounted upon the said arbor and abutted at one end against the said shoulder against which it is rotated with the production of friction, a center-wheel car- 110

ried by the said pinion, a friction-collar non-rotatably mounted on the said arbor adjacent to the opposite end of the said center-pinion from the said shoulder, and a friction washer interposed between the center-pinion and the said friction-collar, one of the two surfaces between which the said washer is interposed being convex and the other being concave, and the washer being compressed and placed under tension between the said surfaces and developing more

or less friction between the opposite end of the center pinion and the said shoulder according to the degree to which the washer is cupped between the two surfaces.

In testimony whereof, I have signed this specification in the presence of two subscribing witnesses.

FREDERICK WEHINGER.
